CLAIM

An ornamental design for a compact disc file, as shown and described.

DESCRIPTION

FIG. 1 is a perspective view of a compact disc file showing our new design;

FIG. 2 is a top plan view thereof;

FIG. 3 is a front elevational view thereof;

FIG. 4 is a left side elevational view thereof;

FIG. 5 is a right side elevational view thereof; and

FIG. 6 is a rear elevational view thereof.

The compact disc file is shown with the hinged front door element in its normal closed position. It is also shown with optional traction pads. The compact disc file will ordinarily be utilized in an exposed manner in homes and businesses.
